UNITED STATES PATENT OFFICE.

HENRY C. WATTS, OF FAYETTEVILLE, TENNESSEE.

BILL AND LETTER FILE.

977,494.

Specification of Letters Patent. Patented Dec. 6, 1910.

Application filed April 8, 1910. Serial No. 554,248.

To all whom it may concern:

Be it known that I, HENRY C. WATTS, a citizen of the United States, residing at Fayetteville, in the county of Lincoln and State of Tennessee, have invented a new and useful Bill and Letter File; and I do hereby declare the following to be a full, clear, and exact description of the invention, such as will enable others skilled in the art to which it appertains to make and use the same.

The invention relates to a letter and bill file and has for its object to provide a device of this character consisting of a base, two uprights and a locking member on the end of each upright, for preventing letters and bills from becoming accidentally displaced.

With these and other objects in view, the invention consists in the novel construction and arrangement of parts hereinafter described and shown and particularly pointed out in the appended claims.

In the drawings:—Figure 1 is a perspective view of a bill and letter file constructed in accordance with this invention. Fig. 2 is a vertical sectional view through one of the uprights. Fig. 3 is a vertical sectional view taken at right angles to Fig. 2. Fig. 4 is a transverse sectional view taken on line 4—4 of Fig. 2. Fig. 5 is a transverse sectional view taken through one of the locking members.

Referring to the drawings, 1 designates a base which preferably consists of a piece of ordinary board having two annular recesses 3, which receive the annular disks or plates 4, from which the posts 5 upwardly project. These posts are made integral with the disks or plates, as clearly shown. The upper end of each post is provided with a recess 6, in which is inserted the upwardly ending L-shaped projection 7. The L-shaped projection 7 is rigidly connected to the post 5, and as shown in Fig. 2, connects with the locking member 8. The locking member 8 is provided with a spring 9, which presses against the upper end of the vertical projection 7 so that the locking member 8 can be held in a vertical or horizontal position, as shown in Fig. 1 of the drawings. The posts

5 are designed to engage the apertures of the bill heads or letters, or if the bill heads or letters are not provided with the same, points of the locking members 8 are designed to pierce the same. When the locking members are in a vertical position, the reduced portion 10 is adapted to be received in the recess or cutaway portion 6, so that the letters or bill heads can be taken off or placed on the arms 5, without mutilating the same.

What is claimed is:—

1. A bill or letter file comprising a base having annular recesses adjacent one end thereof, vertically arranged posts projecting upwardly from the base and provided with annular disks or plates received in said annular recesses, screws penetrating the annular disks or plates to hold the posts in their fixed positions, said posts being cylindrical in form and having their upper portions provided with vertically arranged recesses, projections arranged vertically in said recesses, members fulcrumed to the upper ends of said projections adapted to be held in horizontal or vertical positions and provided with restricted portions to be received by said recesses when the members are in vertical positions, said restricted portions having their outer faces convexed to conform approximately with the cylindrical contours of the posts, as and for the purpose specified.

2. A file of the class described, comprising vertically disposed posts, a recess formed in the upper end of said posts, locking members carried by said posts and having means for holding the same in a horizontal or vertical position, said locking members having a reduced portion adapted to be received into said recesses, when the locking members are in a vertical position.

In testimony whereof I have signed my name to this specification in the presence of two subscribing witnesses.

HENRY C. WATTS.
